ROY R. STEVENS

BY *Wm. M. Cady*

ATTORNEY

UNITED STATES PATENT OFFICE

ROY R. STEVENS, OF FOREST HILLS, PENNSYLVANIA, ASSIGNOR, BY MESNE ASSIGNMENTS, TO CARDWELL WESTINGHOUSE COMPANY, OF CHICAGO, ILLINOIS, A CORPORATION OF DELAWARE

FRICTION DRAFT GEAR

Application filed October 27, 1928. Serial No. 315,398.

This invention relates to friction draft rigging for railway cars and more particularly to that type of friction draft rigging in which a plurality of cooperating wedge blocks 5 are employed to assist in producing the desired frictional resistance to draft and buffing impacts.

In the use of friction draft rigging employing one or more centrally arranged wedge blocks and two side wedge blocks cooperating therewith to assist in producing the desired frictional resistance, it has been discovered that there is a tendency of one side wedge block to begin to move longitudinally before the other, and when one of the blocks does move in advance of the other, the centrally arranged wedges are diverted from the longitudinal center line of the draft rigging and the wedges are worn unevenly. Further, it has been found that when one of the side wedges moves in advance of the other and the longitudinal wedges are diverted from their normal paths of travel, the draft rigging will not readily return to its normal release position.

The principal object of my invention is to provide a friction draft rigging which will be free from the above objectionable features.

Another object of my invention is to provide the side wedge blocks of a friction draft rigging with interengaging means whereby the simultaneous longitudinal movement of the blocks is insured and whereby the blocks are free to move in transverse directions toward and away from each other.

Other objects and advantages will appear in the following more detailed description.

In the drawings, Figure 1 is a horizontal sectional view of a portion of the friction draft rigging embodying my invention; and Fig. 2 is a cross sectional view of the same taken on the line 2-2 of Fig. 1.

In accordance with the drawings, the shock absorbing mechanism of the draft rigging may comprise a hollow rectangular casing 1 containing at its forward end, groups of alternated friction plates 2 and 3 which are disposed at opposite sides of a wedging mechanism, the plates 3 being an-

chored to the casing 1 and the plates 2 being movable relative to the plates 3 under buffing or pulling impacts. Also contained within the casing are coil springs 4, 5 and 6. The wedging mechanism comprises longitudinally disposed wedge blocks 7 and 8 having opposed wedging faces adapted to engage corresponding wedging faces of wedge blocks 9 and 10, the block 9 being disposed at one side of the wedge blocks 7 and 8 and the block 10 being disposed at the other side of the blocks 7 and 8. A follower plate 11 is disposed within the casing 1 and engages the inner ends of the friction plates 2, said follower being engaged at the opposite side by the springs 4 and 5. The wedge block 8 is normally engaged by the follower plate 11.

The wedge block 7 is acted upon by the spring 6 through the medium of a stem 12 extending through an opening in the wedge block 8 and a spring follower 13 which engages the inner end of the stem 12 within the wedge block 8.

The inner facing sides of the wedge blocks 9 and 10 are each provided with top and bottom shoulders 14 and 15, respectively, which overlap the respective top and bottom surfaces of the stem 12 and are adapted to engage the stem to prevent unintentional vertical movement of the wedge blocks.

Projecting from the inner side of the wedge block 9, and disposed above the stem 12, there is a lug 16 which is adapted to engage the wedge block 10 within a socket or recess 17 formed therein, and projecting from the wedge block 10, and disposed below the stem 12 there is a like lug 18 which is adapted to engage the wedge block 9 within a socket or recess 19 formed in the block 9.

The sockets 17 and 19 are of such depth as to permit free movement of the wedge blocks 9 and 10 in directions toward and away from each other, while the diameters of the sockets are such that the lugs 16 and 18 fit in them in such a manner that longitudinal movement of one block relative to the other is prevented.

It will be noted that the wedge blocks 9 and 10 cooperate with each other to insure the simultaneous parallel longitudinal move-

ment of both blocks and at the same time permit free movement of the blocks in directions toward and away from each other, and cooperate with the stem 12 to prevent unintentional vertical movement of the blocks. It will be noted further that by the cooperation of the wedge blocks with each other, the alignment of the ends of the wedge blocks will be maintained against any tendency of one block to move to a position in advance of the other.

While one illustrative embodiment of the invention has been described in detail, it is not my intention to limit its scope to that embodiment or otherwise than by the terms of the appended claim.

Having now described my invention, what I claim as new and desire to secure by Letters Patent, is:—

20 In a friction cushioning mechanism, the combination with a casing, of a wedging mechanism mounted in said casing and comprising a centrally arranged wedge block, a stem carried by said wedge block, two side wedge blocks adapted to be moved longitudinally and transversely of the casing by said centrally arranged wedge block, means for connecting said side wedge blocks to cause them to move in unison, means on said side wedge blocks adapted to engage said stem to prevent unintentional vertical movement of said side wedge blocks relative to said stem, and means for releasing the wedging mechanism.

35 In testimony whereof I have hereunto set my hand, this 23rd day of October, 1928.

ROY R. STEVENS.
